UNITED STATES PATENT OFFICE.

JOHN DOERING, OF NEW YORK, N. Y.

LANTERN.

No. 802,917.

Specification of Letters Patent.

Patented Oct. 24, 1905.

Application filed May 18, 1905. Serial No. 261,012.

To all whom it may concern:

Be it known that I, JOHN DOERING, a citizen of the United States of America, residing in the borough of Brooklyn, city of New York, county of Kings, State of New York, have invented an Improved Lantern, of which the following is a specification.

The object of my invention is to provide an improved construction of lantern which shall 10 be very strong yet economical to make in the guard-frame and in the hinging of the cover, will give a good system of draft without danger of the flame being blown out, and will permit the oil-pot to be withdrawn from the 15 bottom of the lantern and yet permit the wick to be raised or lowered without withdrawal of the oil-pot.

In the accompanying drawings, Figure 1 is an elevation of my improved lantern. Fig. 20 2 is a sectional plan on the line 2 2, Fig. 1. Fig. 3 is a vertical section view on the line 3 3, Fig. 1, but showing the oil-pot being withdrawn. Fig. 4 is a sectional plan on the line 4 4, Fig. 3. Fig. 5 is a similar plan view 25 with the oil-pot adjusted to position and with the frame omitted. Fig. 6 is a face view of diaphragm taken from the hood, and Fig. 7 is a view of a detail.

In the figures, A is the guard and supporting frame; B, the globe; C, the globe-supporting ring; D, the oil-pot, and E is the top or cap, which is hinged at one side e to the top ring A' of the guard-frame and at the other side has a spring-latch e' to engage the 35 top ring A' to hold the cap in its closed position.

The construction of the guard-frame is one of the features of my invention. This frame is composed of a series of flat metal upright 40 strips or bars 5 6, arranged in pairs side by side for about two-thirds of their length from the bottom upward and preferably riveted together, but with their upper ends 5' 6' branched laterally to meet the adjacent 45 branched bars of the adjacent pairs. The upper ends of these united branches 5' 6' are riveted or otherwise secured to the top ring A', which is preferably flanged. The lower ends of the strips or bars 5 6 are shaped with 50 an outward flare, as shown in the drawings, to form a base for the lantern of suitable diameter, and they are united and at the same time spaced by a bottom ring of wire A². The described construction of guard-frame is very 55 strong and rigid.

The globe-supporting ring C is preferably

formed of two sheet-metal rings d d' spun over each other, with an inwardly-projecting flange 7 at the lower end to receive and support the oil-cup and with outwardly-projecting 60 lugs 8 radially notched to receive the inwardly-projecting parts of the united pairs of strips or bars 5 6. The lugs 8 are long enough to have their outer ends wrapped over a wire 9, which passes through all the bars 5 6. 65

The oil-pot is formed with a slightly-reduced upper part 10 and an annular shoulder 11, the reduced part 10 fitting within the flanged lower end of the ring C, which supports the globe B. On the upper edge of this reduced 70 part 10 I provide two diametrically opposite lugs 12 13, and at one side the flange 7 is cut away at 14 to permit one of these lugs 13 to pass through it. To put the lamp in place, one of the lugs 12 is introduced over the flange 7 at 75 a point diametrically opposite the notch 14, whereupon the oil-pot may be tipped upward, as indicated by the arrow in Fig. 3, to pass the other lug 13 through the notch 14 in the flange 7, and at the same time the laterally-projecting 80 wick-raising spindle 17 passes up into a notch 15 cut in the ring C, as indicated by dotted lines in Fig. 3 and partially by full lines in Figs. 4 and 5. Then the oil-pot is turned—say, in the direction of the arrow, Fig. 4—so that 85 the lug 13 will pass laterally away from the notch 14 and into engagement with the flange 7, locking the oil-pot in place with an action like that of a bayonet-joint. To permit this turning movement of the oil-pot, the burner 90 16, with its wick-raiser 17, is not screwed up tight to its seat when the pot is being introduced into the lantern, as shown in Fig. 3, so that the turning of the oil-pot in the direction of the arrow, Fig. 4, and to the position 95 Fig. 5 while the wick-raising spindle is held in the notch 15 will serve to screw the burner to its seat. The friction will hold the parts in position until the oil-pot is intentionally turned back to take it out of its carrying-ring 100 by movements the reverse of those by which the pot was put in place. The described construction of oil-pot attachment is designed to prevent any material admission of air-draft to the flame from below, the top admission 105 hereinafter described being relied on to feed the flame.

The cap or top E has the usual cylindrical dome 20, closed at the top, with outlet draft-openings 21 near the top, and it has also the usual reflector part 22. Within the dome is an annular diaphragm 23, with a series of

projections 24 (four in the present instance) on its lower face to rest upon the top of the globe B, so as to leave between the projections spaces for the admission of fresh air 5 over the top of the globe, which incoming currents of air are directed downwardly by the downwardly-projecting flange 25 on the diaphragm, Fig. 3. These currents of fresh air pass down along the inner face of the globe 10 to the flame, while products of combustion pass upward in a central column and out through the center of the diaphragm 23 into the dome. A draft-producing cone 26 may be provided over the diaphragm 23, and a 15 ring of holes 27 may be made in the diaphragm 23 to admit air to the dome outside and also inside the cone. The diaphragm and cone may be secured together, and they can move up and down within the dome; but a light 20 spiral spring 28 within the dome presses the diaphragm down onto the globe.

As a convenient way to hinge the cap E to the frame I split the top ring A' and flange its adjacent ends at 30, and I rivet to the cap a 25 lug 31, which passes between the flanges 30, Figs. 1 and 3. A hinge-pin formed of a detachable nut and screw 32 completes the attachment, so that the cap E may be wholly taken off when required.

30 The bail F may be secured to the lantern in any suitable way, as by bending adjacent branches 5' 6' to form sockets f for hinge-pins 33 on the ends of the bails, Figs. 1 and 7. These branches may be riveted together at 34.

35 I claim as my invention—

1. A guard-frame for a lantern, comprising

a series of upright bars in pairs with their upper ends branched laterally and joined to adjacent branches and with top and bottom rings.

2. A guard-frame for a lantern, comprising a series of upright bars riveted together in pairs and branched laterally at their upper ends, a bottom ring spacing the pairs, and a top ring to which the tops of the bars are 45 riveted.

3. In a lantern, the combination of a guard-frame, with a globe-holding ring in two parts spun over each other, one part presenting outwardly-projecting lugs connecting to the 50 guard-frame and the other part projecting inwardly to form an inwardly-projecting flange to support the oil-pot.

4. In a lantern, the combination of a frame and notched ring with an oil-pot detachable 55 from below and having a wick-raiser and a burner screwed into the oil-pot, the wick-raising spindle being adapted to enter the notch in the ring and to be accessible from the outside of the lantern, and a bayonet-joint 50 to secure the oil-pot in the frame with a rotary motion of the oil-pot, the said burner being adapted to be screwed into the oil-pot by turning the latter into the bayonet-joint.

In testimony whereof I have signed my name 65 to this specification in the presence of two subscribing witnesses.

JOHN DOERING.
